(57) **CLAIM**

The ornamental design for a pet paw cleaner as shown and described.

DESCRIPTION

FIG. 1 is a top, front and left side perspective view of a pet paw cleaner showing our new design;
FIG. 2 is a top, front and right side perspective view thereof;
FIG. 3 is a bottom, front and left side perspective view thereof;

FIG. 4 is a top and front perspective view thereof;
FIG. 5 is a front elevational view thereof;
FIG. 6 is a rear elevational view thereof;
FIG. 7 is a left side view thereof;
FIG. 8 is a right side view thereof;
FIG. 9 is a top plan view thereof;
FIG. 10 is a bottom plan view thereof; and,
FIG. 11 is a cross-sectional view taken along line 11-11 of FIG. 7.
The broken lines in the drawings illustrate portions of the pet paw cleaner which form no part of the claimed design.

1 Claim, 11 Drawing Sheets
